Primary Examiner — George D. Kirschbaum

(57) **CLAIM**

The ornamental design for a bingo game table, as shown and described.

DESCRIPTION

FIG. 1 is a front perspective, in-use view of a bingo game table showing my new design;

FIG. 2 is another front perspective view thereof;

FIG. 3 is a front view (back view is mirror image) thereof; FIG. 4 is a side view (opposite side view is mirror image) thereof;

FIG. 5 is a top view thereof; and,

FIG. 6 is a bottom view thereof.

In FIG. 1, the broken lines showing of environment structure for the purpose of illustrating the bingo game table in a condition of use. The broken lines and the structure they depict form no part of the claimed design.

1 Claim, 4 Drawing Sheets(56)
